UNITED STATES PATENT OFFICE.

JOSEPH E. BOHNER, OF ANSONIA, CONNECTICUT, ASSIGNOR TO THE
WALLACE & SONS, OF SAME PLACE.

DESIGN FOR A TABLE-LEG.

SPECIFICATION forming part of Design No. 24,924, dated November 26, 1895.

Application filed October 8, 1895. Serial No. 565,082. Term of patent 3½ years.

To all whom it may concern:

Be it known that I, JOSEPH E. BOHNER, a citizen of the United States, residing in Ansonia, in the county of New Haven and State 5 of Connecticut, have invented and produced a new and useful Design for Table-Legs, of which the following is a specification, reference being had to the accompanying drawing, which illustrates the design.

10 In the accompanying drawing the dotted lines represent a table-top, and the full lines represent different views of a table-leg of the present design.

15 The general form of the leg is incurving, as shown, or curving to beneath the table.

A represents the leg or the main body thereof. B represents the foot thereof, the

design of which is of the foliate-scroll form shown.

At the top of the leg is the oval disk C, surrounded by conventionalized leaf and shell like ornaments D and E. 20

The main body of the leg is ornamented by foliate forms F and G.

The leading features of the design are those 25 above indicated.

What is claimed as new is—

The design for a table leg, substantially as shown and described.

JOSEPH E. BOHNER.
